ELEVATED TOILET SEAT

Eugene B. Weidner, 622 Cypress St., and Jacob Geppert,
1412 Cypress St., both of Highland, Ill.

Filed Apr. 11, 1960, Ser. No. 60,131

Term of patent 14 years

(Cl. D4—5)

FIG. 1

FIG. 3

FIG. 1 is a top perspective view of an elevated toilet seat embodying our new design;

FIG. 2 is a side elevational view thereof, the opposite side being substantially the same, and

FIG. 3 is a bottom plan view thereof.

The characteristic features of our design reside in the support legs having the configuration shown.

We claim as our invention:

The ornamental design for an elevated toilet seat, substantially as shown and described.
